CHEMICAL VAPOR DEPOSITION REACTOR

William George Faraco, Jr., 13561 Howen Drive,
Saratoga, Calif. 95070

Filed Sept. 4, 1973, Ser. No. 393,268

Term of patent 14 years

Int. Cl. D15—99

U.S. Cl. D55—1 R

FIG. 2

FIG. 1

FIG. 1 is a front elevational view of the improved chemical vapor deposition reactor embodying my new design.

FIG. 2 is a side elevational view of one side thereof.

FIG. 3 is a side elevational view of the opposite side thereof.

FIG. 4 is a top plan view thereof.

I claim:

The ornamental design for a chemical vapor deposition reactor, substantially as shown.
